UNITED STATES PATENT OFFICE.

HOWARD W. COTTON, OF ROCHESTER, NEW YORK.

BICYCLE-LOCK.

SPECIFICATION forming part of Letters Patent No. 596,396, dated December 28, 1897.

Application filed December 31, 1896. Serial No. 617,631. (No model.)

To all whom it may concern:

Be it known that I, HOWARD W. COTTON, a citizen of the United States, residing at Rochester, in the county of Monroe and State of New York, have invented a new and useful 5 Bicycle-Lock, of which the following is a specification.

This invention relates to locks especially designed for securing bicycles and like road 10 vehicles or machines when not required for immediate service and which embody in their construction an arm to be turned across the path of a wheel or moving part, so as to secure the same against rotation, said arm being held in the projected position by locking 15 devices which form the basis of the present invention.

For a full understanding of the merits and advantages of the invention reference is to 20 be had to the accompanying drawings and the following description.

The improvement is susceptible of various changes in the form, proportion, and the minor details of construction without departing 25 from the principle or sacrificing any of the advantages thereof, and to a full disclosure of the invention an adaptation thereof is shown in the accompanying drawings, in which—

30 Figure 1 is a perspective view of a lock embodying the features of this invention. Fig. 2 is a front view thereof, the dotted lines showing the position of the locking-arm when the latter is turned out of the path of the moving part or wheel. Fig. 3 is a longitudinal section showing the clamp in elevation and the relation of the parts when the locking-arm is turned out of the path of the moving 35 part. Fig. 4 is a longitudinal section showing the relation of the tumblers when the rotary bolt is released. Fig. 5 is a view similar to Fig. 4, showing the rotary bolt locked. Fig. 6 is a section on the line X X of Fig. 5, looking to the right. Fig. 7 is a section on the line Y Y of Fig. 3, looking to the right.

45 Corresponding and like parts are referred to in the following description and indicated in the several views of the drawings by the same reference-characters.

50 The lock comprises a clamp 1, a case 2, containing the locking mechanism and having the clamp rigidly connected therewith, and a

locking-arm 3. The case is formed with an offset 4, to which one end of a flexible band 5 is attached and which has longitudinal perforations for the passage therethrough of clamp-screws 6, by means of which the clamp-band 5 is drawn tightly about a fork member or frame-bar of a machine or part to which the lock is to be applied. A block 7 is secured 55 to the free end of the clamp-band 5 and has threaded openings to receive the threaded ends of the clamp-screws 6, by means of which the band 5 is caused to firmly grip the part to which the lock is applied. By having the 60 clamp-band 5 flexible it will readily conform to the shape of the frame-bar, fork, or other part to which it is fitted and engage the same frictionally throughout its extent, thereby preventing any movement of the lock upon 65 the part when properly applied.

The case has longitudinal openings 8 at its inner end to receive tumblers or pins 9, which are held projected by springs 10, located at the inner ends of the openings and exerting 70 an outward pressure against the inner ends of the said tumblers. The rotary bolt 11, revolvably fitted in the outer end of the case, has openings which are adapted to register with the openings 8 and has pins or tumblers 80 12 fitted therein, and which are of unequal length, so as to prevent the opening of the lock except by the use of a key especially fitted thereto. Slots or key-openings 13 extend outwardly from the openings receiving 85 the pin-tumblers 12 to provide passages for the entrance of the key 14 when it is required to open the lock. The locking-arm 3 is secured to or formed with the rotary bolt, and its inner end is of circular outline and of 90 such relative size as to overlap the end of the case and the heads of the clamp-screws 6, so as to prevent a withdrawal of the latter by unauthorized parties. A semicircular notch 15 is formed in an edge of the circular end of 95 the locking-arm, and when the latter is released it can be turned so as to bring the notch in register with the clamp-screws, thereby making provision for placing them in position or removing them, as may be required. The notch 15 is so disposed that when the arm 3 is turned across the path of the part to be secured it will be out of register with the clamp-screws, as clearly indicated 100.

in Figs. 1 and 2. A key 16 is let into a transverse kerf in the case and is secured thereto by calking or in any other substantial manner, and its inner edge 17 enters a transverse groove 18 in the rotary bolt and holds the latter in place, and the projecting portion 17 forms a ward to enter a notch in an edge of the key 14, so as to retain the latter in place when turning the rotary bolt from a locked 5 to an unlocked or normal position, and also increases the difficulty of opening the lock by a key or other means not specially constructed for the purpose. A packing-ring or rubber gasket 19 is interposed between the end of 10 the case and the inner end or head of the locking-arm 3 and is seated in a groove formed in the end of the case. This packing renders the lock proof against dust and moisture.

The key 14 is cleft, forming prongs or members 20, of unequal length, corresponding with the differential length of the pin-tumblers 12, whereby the combined length of the prongs 20 and the corresponding tumblers 12 is equal, so that when the key is thrust into the lock 25 the pin-tumblers 9 will be depressed to a plane corresponding with the joint formed between the rotary bolt and the opposing end of the case, thereby admitting of the rotary bolt turning, so as to withdraw the locking-arm 3 from the path of the moving part. The ends 30 of the prongs 20 are notched to receive central projections at the outer ends of the tumblers 12, whereby an additional safeguard is provided against the surreptitious opening of 35 the lock.

A spring-actuated dog 21 is located in an opening formed at the inner end of the case, and its outer end is made tapering or rounding, so as to project a short distance into an 40 opening in the rotary bolt provided to receive a pin-tumbler, so as to hold the locking-arm in a normal position when withdrawn from the path of the wheel or moving part, thereby preventing its accidental displacement when 45 the machine is passing over rough places or otherwise subjected to vibration. This spring-actuated dog acts as a retainer and positively holds the locking-arm in a predetermined position and against accidental displacement, 50 but does not prevent the turning of the said arm on the application of sufficient force thereto.

The lock is intended to be applied to the fork of a bicycle, so that the locking-arm 3 can be projected across the path of the spokes adjacent to the rim, thereby preventing the turning of the front wheel when the machine is left standing or not required for immediate service.

Having thus described the invention, what is claimed as new is—

1. In a lock for bicycles and like machines, the combination of a flexible clamp-band, a lock applied to one end of the clamp-band, 65 an offstanding part at the opposite end of the clamp-band and provided with a threaded opening, a clamp-screw for connecting the

lock and said offstanding part and drawing the clamp-band about a frame-bar of the machine, and a locking-arm having a portion 70 projecting over the head of the clamp-screw to prevent loosening thereof when the lock is in operative position, substantially as set forth.

2. In combination, a lock-case having an 75 offset portion, a flexible clamp-band secured at one end to the said offset, a block applied to the opposite end of the clamp-band and having a threaded opening, a clamp-screw passing through the said offset and entering 80 the threaded opening of the block, and a locking-arm for securing the clamp-screw in place, substantially in the manner set forth.

3. In a lock, the combination of a case having a series of longitudinal openings at its 85 inner end, spring-actuated tumblers located in the said openings, a rotary bolt secured in the outer end of the case and having longitudinal openings at its inner end corresponding in number and position with the longitudinal openings of the case, and having longitudinal slots in its sides extending outward from the longitudinal openings, forming key-passages which are closed at their outer side by the inner wall of the case, key-operated 90 tumblers of unequal length fitted in the said openings of the rotary bolt, and a locking-arm secured to the outer end of the rotary bolt, substantially as and for the purpose set forth. 100

4. In a lock, the combination of a case, spring-actuated tumblers located in openings of the case, a rotary bolt fitted within the case and having a locking-arm, a key secured in a transverse groove of the case and extending into a corresponding groove of the rotary bolt to hold the latter in place, form a ward, and provide a means for holding the operating key in place when opening the lock, and key-operated tumblers located in 110 openings provided in the rotary bolt, substantially as specified.

5. In a lock, the combination with a case having a spring-actuated tumbler, a rotary bolt revolvably secured within the case and bearing a locking-arm, and a key-operated tumbler carried by the rotary bolt, of a spring-actuated dog located in an opening of the case to one side of the aforesaid tumbler and adapted to enter the opening of the rotary bolt provided to receive the said tumbler to hold the locking-arm normally out of action and against accidental displacement, substantially as and for the purpose set forth. 120

6. A lock for bicycles and like machines, 125 comprising a case having an offset, a flexible clamp-band secured to the offset at one end, a block at the opposite end of the clamp-band having a threaded opening, a clamp-screw for adjustably connecting the block 130 with the aforesaid offset, spring-actuated tumblers located within the case, a rotary bolt operating within the case, key-operated tumblers of unequal length carried by the

rotary bolt, a spring-actuated retaining-dog for holding the rotary bolt in a normal position, and a locking-arm applied to the rotary bolt and having its inner end expanded and extending over the head of the clamp-screw to prevent tampering therewith when the locking-arm is performing service, substantially as set forth.

In testimony that I claim the foregoing as my own I have hereto affixed my signature in the presence of two witnesses.
